UNITED STATES PATENT OFFICE

SIDNEY B. BLAISDELL, OF WYNCOTE, PENNSYLVANIA, ASSIGNOR TO FIDELITY MACHINE COMPANY, OF WILMINGTON, DELAWARE, A CORPORATION OF DELAWARE

BEAT-UP MECHANISM FOR BRAIDING MACHINES

Application filed June 18, 1930. Serial No. 462,016.

This invention relates to mechanism for beating up or closely packing the threads of a braided product at the braiding point of a braiding machine during the formation of the product, and is particularly adaptable for use with a machine making a braided product having a relatively large number of ends or threads interbraided together, such as that shown and described in my prior United States Patent No. 1,742,126, dated Dec. 31, 1929.

The construction and operation of the mechanism forming the subject of the present invention will be fully described hereinafter, reference being had to the accompanying drawings, of which:

Fig. 1 is a rear elevation of a braiding machine showing the beater applied thereto;

Fig. 2 is a sectional plan view taken on the line 2—2, Fig. 1;

Fig. 3 is a view similar to Fig. 2; drawn on an enlarged scale;

Fig. 4 is a sectional elevation taken on the line 4—4, Fig. 3; and

Fig. 5 is a side view of a detail of the invention.

The braiding machine comprises a main bed plate 1 supported by legs 2, 2. Supported by posts 3, 3 from the bed plate 1 is a bobbin carrier supporting platform 4, between which and the base plate 1 is rotatably mounted a plurality of horn gears 5, having horns 6 adapted to engage depending projections 7 that extend downwardly from the bobbin carriers 8; on the platform 4, through slots 9 formed in the bobbin carrier supporting platform 4.

The slots 9, diagrammatically illustrated in Fig. 2, function as guides for the bobbin carriers 8 to effect interbraiding of the threads 10 which are drawn from bobbins 11 supported by the carriers 8; the threads 10 passing from guide posts 12 on the carriers to the braiding point Y at the lower end or mouth of the braiding mandrel or tube 13, which is supported above the platform 4 and the carriers mounted thereon; the finished product X passing upwardly through the tube 13 to and between a pair of take-up rolls 14 and 15.

The horn gears 5 intermesh one with an-

other and at opposite sides of the machine with gears 16 and 17 which are respectively secured to vertically extending shafts 18 and 19. On the lower end of the shafts 18 and 19 are secured beveled gears 20, 20 that mesh respectively with a beveled gear 21, 21 secured to the opposite ends of a main horizontally disposed shaft 22 which is provided with a driving pulley 23.

Secured to and extending upwardly from the bed plate 1 at the opposite sides thereof are standards 24 and 25, which support a horizontally disposed bridge beam 26.

The upper end of the vertical shaft 18 is rotatably mounted in a bearing 27 secured to the bridge beam 26 while the lower end of said shaft is rotatably mounted in bearings 28 and 29 formed in a bracket 30 secured to the bed plate 1.

The upper end of the vertical shaft 19 is rotatably mounted in a bearing 31 secured to the standard 25, and the lower end of said shaft is rotatably mounted in bearings 32 and 33 formed in a bracket 34 secured to the bed plate 1.

The opposite ends of the main horizontal shaft 22 are rotatably mounted in bearings 35 and 36 formed respectively in the brackets 30 and 34.

The take-up roll 14 is secured to one end of a horizontal shaft 37 which is rotatably mounted at one end in a bearing 38 secured to the bridge beam 26 and at its opposite end in a bearing 39 secured to or formed in the standard 25.

The bearing 38 is provided with a bracket 40 in which is secured a stud 41, and on the stud 41 the take-up roll 15 is rotatably mounted.

The take-up shaft 37 is provided with a gear wheel 42 which meshes with a gear wheel 43 that is rotatably mounted on a stud 44 supported by the standard 25. On the hub of the gear 43 is a worm wheel 45 that meshes with a worm 46 secured to the vertical shaft 19.

The mandrel tube 13 is supported for vertical adjustment in a holder 47 supported by rods 48, from a plate 49 that is secured to the bridge beam 26.

As the shaft 22 is rotated the carriers 8 are moved through various intertwining paths, and in various directions to effect interbraiding of the threads 10 at the mouth 5 of the mandrel tube 13 and in order to produce a more compactly formed product I provide at the mouth of the mandrel tube 13 a plurality of beaters 50, arranged around the mouth of the tube 13, as clearly illustrated in Figs. 2 to 5 inclusive, the beaters being adapted for movements in planes extending radially from the axis of the mandrel tube.

Each of the beaters 50 comprises a substantially straight body bar 51 having a series of pins 52 extending longitudinally from one end of the bar 51, thereby forming a comb, the teeth of which move into position between the crossed and interbraided threads 10 at a point removed from the mandrel and then move in a substantially straight line parallel to the plane of the crossed thread to a point immediately adjacent the mouth 20 of the mandrel tube 13 which beats or packs the crossed threads tightly at the braiding point Y, located at the mouth of the mandrel tube 13.

The teeth 50 of the beater combs are then withdrawn from the beaten product and travel in a reverse direction above the plane of the threads then being crossed and interbraided by the actions of the bobbin carrier 8, the comb teeth 52 then reentering the crossed threads at the above mentioned remote point for a repeat of the operation just described.

Upon referring to Figs. 4 and 5, the action of the beater comb will be quite apparent, 40 the teeth 52 entering between the crossed threads 10 (see Fig. 2, for the crossing of the threads) at the point y, following a downward path y^1 in entering the plane of the crossed threads 10, thence through a long 45 arcuate path y^2 which is substantially straight and parallel to the plane of the cross threads 10, then gradually curving upward to the plane of the cross threads and leaving the plane of the crossed threads immediately 50 adjacent the mouth of the mandrel tube 13, as illustrated at y^3 . The comb teeth 52 then travel in a reverse direction above the plane of the threads 10, reentering the plane of the threads at the point y for a repeat of the 55 operation.

The teeth 52, as is apparent from the drawings and the above description, describe a substantially elliptical path, which is accomplished by pivotally mounting each beater bar 51 on a crank pin 53 at a point spaced from and behind the comb teeth 52, the opposite end of the bar 51 sliding between and being guided by spaced guides 54, 54.

65 In the present instance the crank pin 53

projects laterally from a gear 55, which constitutes the crank arm, the gear being rotatably mounted on a fixed bracket 56 which also functions as a support for the guide pins 54, 54.

70 The brackets 56 are secured to an upper or supplementary bed plate 57 which is supported at one side from the bridge beam 26 by rods 58, 58, the opposite side of the bed plate 57 being supported from the main bed plate 1 of the machine by arms 59, 59, mounted in bearing blocks 60, 60 which are supported by standards 61, 61 secured to and projecting upwardly from the main bed plate 1.

75 The gear wheels 55 each mesh with a gear 62, which is secured to a shaft 63. Each shaft 63 is rotatably mounted at one of its ends in one of the brackets 56 and at its opposite end in a bearing 64 secured to the upper bed plate 57. Each shaft 63 is provided with a bevel gear 65 which meshes with a similar gear on the adjacent end of another of the shafts 63, the axes of the shafts 63 forming a square around and having the mandrel tube 13 as its center.

80 One of the shafts 63 is provided with a bevel gear 66 which meshes with a bevel gear 67 secured to the lower end of an upright shaft 68 that is rotatably mounted in a bearing 69 secured to the upper bed plate 57.

85 On the upper end of the vertical shaft 68 is secured a pulley 70 adapted to be driven from a pulley 71 on the vertical shaft 18 by a belt 72 so that the shafts 63 are all driven at the same speed and in timed relation to each other for operating the beaters or combs 50 in timed relation to each other, it being noted from the drawings that no two of the combs 50 are performing the same identical part of their cycle 105 of operation at the same time but follow successively around the machine and the product being produced, thus insuring an even and regular beat up of all the threads completely around the product.

110 I claim:

1. The combination of a braiding machine utilizing a plurality of braiding threads, a beater co-operating with the braiding mechanism and disposed above the braiding threads to compact the threads at the braiding point of the machine, said beater comprising a series of elements disposed around the braiding point above said braiding threads and adapted to enter the braided threads from above and at points removed from said braiding point, and means for advancing the beater elements successively toward the said braiding point, and for withdrawing said elements from said threads adjacent the braiding point of the machine to a return position above said threads.

115 2. The combination of a braiding machine utilizing a plurality of braiding threads, a beater co-operating with the braiding mech- 120 125 130

anism to compact the threads at the braiding point of the machine, said beater comprising a series of elements disposed around the braiding point, each beater element comprising a body element and a plurality of teeth at one end of said body element, a crank rotatably connected to the body element adjacent the toothed end thereof and a guide for the opposite end of the body element whereby upon rotation of the crank the teeth of the body elements enter the braided threads at points removed from the braiding point, advance toward the braiding point, and withdraw from the threads adjacent the braiding point.

3. In a braiding machine employing a plurality of thread guides operating in a common plane through intertwining paths crossing at central, perimetric and intermediate points of a predetermined area of said plane, said machine having a braiding station spaced from said plane and to which the threads extend from said guides in closely massed interlaced and relatively moving relation to each other, a beater comprising a plurality of beater elements disposed around and adjacent said station outside said mass of threads, means for projecting each of said beater elements into said mass at an outer position spaced from said station and for retracting said beater elements from said mass at inner positions immediately adjacent said station and in a direction substantially perpendicular to said plane in corresponding relation to the direction of movement of the resulting product from said station, and means for advancing said beater through said mass

from said outer position to said inner position and for returning said beater to said outer position along a path outside said mass subsequent to the retraction of the beater from said mass.

4. In a braiding machine employing a plurality of thread guides operating in a common plane through intertwining paths crossing at central, perimetric and intermediate points of a predetermined area of said plane, 70 said machine having a braiding station spaced from said plane and to which the threads extend from said guides in closely massed interlaced and relatively moving relation to each other, a beater comprising a plurality of beater elements disposed around and adjacent said station outside said mass of threads, means for projecting each of said beater elements into said mass at an outer position spaced from said station and for 75 retracting said beater elements from said mass at inner positions immediately adjacent said station and in a direction substantially perpendicular to said plane in corresponding relation to the direction of movement of the 80 resulting product from said station, and means for advancing said beater elements through said mass from said outer positions to said inner positions and for returning said beater elements to said outer positions along 85 paths outside said mass subsequent to the retraction of the beater elements from said mass.
